UNITED STATES PATENT OFFICE.

HARRY WARD LEONARD, DECEASED, LATE OF BRONXVILLE, NEW YORK, BY CAROLYN G. LEONARD, ADMINISTRATRIX, OF BRONXVILLE, NEW YORK, ASSIGNEE TO H. WARD LEONARD, INCORPORATED, A CORPORATION OF NEW YORK.

ELECTRIC CONTROLLING MEANS.

1,802,817.

Specification of Letters Patent.

Patented May 6, 1919.

Application filed October 12, 1915. Serial No. 55,405.

To all whom it may concern:

Be it known that HARRY WARD LEONARD, deceased, late of Bronxville, in the county of Westchester and State of New York, has invented certain new and useful Improvements in Electric Controlling Means, of which the following is a full, clear, and exact specification.

This invention relates to electric controlling means and is particularly applicable to the control of electric systems employed on motor cars for lighting, ignition, starting and other purposes. Such a system usually includes a dynamo driven by the engine, a storage battery which is charged by the dynamo and incandescent lamps, ignition means, electric horns, a starting motor and various other translating devices which are supplied from the battery, and at times jointly by the dynamo and battery.

Among the objects of this invention are the provision of a form of construction of a controller which will attain in the highest degree, reliable and proper operation, durability, compactness and the avoidance of the necessity for frequent inspection or repairs.

The present invention in this embodiment thereof, utilizes vibratory contacts for controlling a winding affecting the voltage generated by the dynamo, the vibratory contact or contacts being responsive to fluctuations in the current supplied by the dynamo, although other particular embodiments of this invention and applications thereof may be made without departing from the scope of this invention.

In controlling means of the present type, it is very desirable not only that the vibratory switch should move rapidly and definitely, but that the method of making contact and the relationship of the parts should be such as to insure keeping the contacts clean, and also maintain a positiveness of contact and secure a quick positive breaking of contact. In the preferred embodiment of this invention, the construction is such as to give a pronounced sliding of the contacts at the time of making and breaking, also a quick hammer blow action in breaking contact, and means are also provided whereby the contact is firmly made by rigid means of control. These and other features and advantages of this invention

will be understood from the following description and accompanying drawings.

Figure 1 is a diagrammatic view of one embodiment of my invention also showing the controlling means in plan view; Fig. 2 is a similar diagrammatic view with certain parts omitted and the connections simplified; Fig. 3 is a face view of the vibratory contact, and Fig. 4 is a back view of another controlling contact.

The gasoline engine which serves as the driving engine of the motor car is indicated at 1, and is shown driving a direct current dynamo armature 2. The speed of the dynamo will be directly proportionate to that of the engine either by a direct connection, by gearing or other driving means. Preferably, a shunt wound dynamo is used, the shunt field winding being shown at 3. The armature supplies current to a storage battery 4, which is shown as having three cells giving a battery voltage of about six volts.

The controlling magnet having an iron core 6 and iron pole pieces 7, 7' is provided with two windings, a shunt winding 8 and 80 a series winding 9. At each end of the magnet is supported an armature adapted to be attracted by the pole piece at the opposite end of the magnet. Thus there is secured to the end piece 7 of the magnet an angle 85 piece 10 having rigidly clamped thereto a flexible strip 11 of phosphor bronze or other suitable material. This strip in turn flexibly supports the movable armature 12 having an outer inclined portion 12' bent 90 at an angle to the inner portion 12''. The inclined portion 12' has riveted or otherwise secured to it at 13 as shown in Figs. 1, 2 and 4, a flat spring finger 14 carrying a contact 15 on its inner face 95 projecting through and beyond the inner face of the inclined portion 12'. Opposite the movable contact 15 is mounted a fixed contact 17. Rigidly supported at 10 is a leaf spring 18 engaging the inner face 100 of the inclined armature portion 12' tending to force the armature away from the pole piece 7'. For support and adjustment of this spring 18 a rigid part 19 carries a screw 20 which screw passes through the support 19, which clamps the screw 20 so vibration will not cause it to turn. Said screw 20 also passes through the armature

portion 12" freely and has threaded engagement with the block 21, fixed to the spring 18. It is apparent that turning the screw 20 will adjust the pressure by which the armature 12 is forced away from its pole piece by the spring 18.

When the armature 12 is attracted to the pole piece 7', contact 15 engages the fixed contact 17, the armature 12 moving on the flexible strip 11 as its pivot. After the first engagement of the contact 15 with the contact 17, continued movement of the armature about the pivot 11 will cause the flexible finger 14 to bend away from the armature portion 12' about the pivot 13. This results in a definite sliding of the contact 15 over the contact 17 by reason of the finger 14 moving about the pivot 13 and the armature 12 moving about the pivot 11. As the armature is further attracted this sliding action continues with increased pressure until finally the bridge 16 engages the back of the finger and firmly holds the contact 15 against the contact 17. When the magnetism of the magnet is sufficiently decreased so that the force of the spring 18 overcomes the magnetic attraction, the armature 12 will be forced away from the pole piece 7' and the bridge 16 will release the finger 14. As the movement of the armature from the pole piece continues the contact 15 will slide on the contact 17 by reason of the above described relationship of parts until the armature portion 12' engages the inner face of the finger 14, which will then result in the contact 15 forcibly and quickly breaking contact, the armature giving the finger a hammer blow for separating the contacts. This quick and definite breaking of the circuit at the contacts necessarily results in minimizing the arcing or tendency to arc. Likewise the sliding of the contact 15 across the face of the contact 17 during the engagement and disengagement of the contacts results in keeping the contact faces in good condition, avoiding pitting or roughening of the contacts which still further assists in minimizing the sparking and in securing a definite closing and opening of the circuit.

In a reversed location to the above described armature is another armature 22, pivotally mounted by the flexible strip 23, similar to the strip 11 and fixed to a support 24 at the right-hand end of the magnet. This armature has an inclined outer portion 22' supported from an inner portion 22" and is also provided with a spring 18', arm 19', adjustment screw 20' and block 21' corresponding to the similarly numbered parts above described. On the outer face of the inclined portion 22 of the armature and at its lower end is riveted a finger having two contacts 25, 26, the contact 25 being carried by the portion 27 of the finger and the contact 26 being carried by a portion 28

of the finger as shown in Fig. 3. The finger is in the form of a flat spring, its tension being such that the outer end of the portion 28, which passes under the bridge 29 on the armature 22', normally presses against the underside of the bridge. Similarly, the finger portion 27 passes under the bridge 29 near its outer end and the spring tension tends to normally hold the same against the inner or under side of the bridge. The contacts 25, 26 are adapted to engage fixed contacts 30, 31.

When the magnet is not sufficiently energized to attract the armature portion 22', the spring 18' forces the armature outwardly, the contacts 25, 26 engaging the fixed contacts 30, 31 and the pressure exerted by the spring 18' is such that the face of the armature portion 22' presses against the finger portions 27, 28. When the magnet attracts the armature 22, the armature portion 22' approaches the pole 7 and during the initial movement the contacts 25, 26 remain in engagement with the fixed contacts, and the underside of the bridge 29 moves toward the fingers. During this action, however, there is a sliding movement of the contacts 25, 26, over the face of the fixed contacts by reason of the bending of the fingers about their fixed ends and by reason of the movement of the armature about the flexible hinge strip 23. Continued movement of the armature next causes the bridge 29 to strike against the finger portion 27 with a hammer blow and break the circuit between the contact 25 and the fixed contact 30 giving a quick and definite rupture of the circuit. Further movement next causes the bridge 29 to strike against the finger 28 with a hammer blow and quickly and forcibly breaks the circuit connection between the contacts 26 and 31. When the armature is released by the magnet the contact 26 first engages the fixed contact 31, the finger 28 being forced inwardly from engagement with the bridge 29. After the engagement of contact 26 with its fixed contact, the contact 25 engages its fixed contact 30, the finger 27 being forced from engagement with the underside of the bridge by pressure of the spring 18'. During this action, by reason of the bending of the fingers and movement of the armature about the hinge or pivot 23, the sliding action of the movable contacts over the fixed contacts previously referred to takes place, until the armature portion 22' engages the back of the fingers and holds the contacts firmly in engaged position. Thus, during both the opening and closing movements, the movable contacts are caused to slide over the fixed contacts which keeps the contact surfaces in a smooth and polished condition, which assists in the making and breaking of the contacts being certain and definite and assists in

5 avoiding their deterioration by roughening or pitting of their surfaces. Furthermore, the breaking of the circuit connection at the contacts is by a quick hammer blow action in the manner above described which reduces objectionable arcing and arcing effects to a minimum.

10 The series coil 9 is in circuit between the dynamo armature 2 and battery 4 when the contact 15 engages the contact 17, one terminal of the armature being in electric connection with the pole pieces and core of the magnet so that when the contact 15 engages the contact 17, the current passes from the 15 left-hand magnet pole through the portions making up the armature 12 to the finger 14 and contact 15, then to fixed contact 17 through the series coil 9, through the battery 4 and then back to the other terminal of the 20 dynamo armature. In circuit with the storage battery are any desired translating devices, such as incandescent electric lamps 32, electric horn 33, ignition coils 34, starting motor 35, etc., all connected in parallel with 25 each other across the supply mains.

The shunt coil 8 is connected in shunt across the terminals of the dynamo armature 2, the circuit being represented in Fig. 2 as extending from the upper terminal of the 30 dynamo armature to the end plates and core of the magnet, thence through the shunt coil 8 to the other terminal of the armature. The shunt field winding 3 of the dynamo is also connected in shunt across the armature 35 terminals with a resistance 36 in series therewith, the circuit extending from the upper terminal of the dynamo armature to the magnet end pieces and core, then through the resistance 36 and field winding 3 to the other 40 terminal of the dynamo armature. Between the resistance 36 and the field winding 3 a connection at 37 is shown extending to the fixed contact 30; and from an intermediate point 38 of the resistance a connection is 45 shown as extending to the fixed contact 31. When the armature 22 is attracted by the magnet all of the resistance 36 is placed in series with the shunt field winding across the armature terminals. When the armature 22 is 50 released and connection first made between contacts 26 and 31 as above described, the right-hand section of resistance 36 is short-circuited. The subsequent closing of contacts 25 and 30 causes the remainder of the resistance 36 to be short-circuited. When the armature 22 is 55 attracted, the reverse action takes place, the breaking of the circuit between the contacts 25 and 30 inserting the left-hand portion of the resistance 36 in series with the field winding, followed by the insertion of the remaining portion of the resistance in 60 series with the field winding. With other conditions fixed, the amount of sparking at the contacts 25 and 30 when they are separated to insert the left-hand portion of re-

sistance 36 will be approximately proportionable to the amount of the inserted ohmic resistance, but after such resistance is once inserted in series with the field the amperes of the circuit, which include the field winding 3 70 and the left-hand portion of resistance 36, is considerably reduced, which would permit the right-hand portion of the resistance being made considerably higher with the same amount of sparking as exists when the left-hand portion of the resistance is inserted. In practice it is found that the second step of resistance inserted can be several times the amount of resistance inserted in the first step with the same sparking on their respective contacts; but when the second step inserted is made much larger than the first step, it is essential that the steps of resistance shall be inserted in their proper order, and this is positively assured by the above 85 described construction.

Assuming that the dynamo is being driven by the engine 1 or other source of power, at a speed such as to cause the voltage generated by the dynamo armature to approach or equal 90 that of the storage battery 4, the current through the shunt or voltage winding 8 will be such as to cause the armature 12 to be attracted and the circuit closed between the contacts 15 and 17 as above described, which 95 connects the charging dynamo to the circuit with the coil 9 in series. At the time of closing the charging circuit the excitation of the controlling magnet is not sufficient to attract the armature 22 with the result that 100 the resistance 36 is short-circuited giving a strong field excitation of the dynamo. The voltage generated by the dynamo armature by reason of this strong field continues to increase resulting in a gradually increasing 105 charging current passing to the battery from the dynamo armature through the series coil 9. The magnetomotive force of this coil being additive to that of the voltage coil 8, the magnetization of the controlling 110 magnet gradually increases until the armature 22 is attracted placing the resistance 36 in series with the field winding 3 by steps in the manner above described. The resistance 36 is so highly proportioned that its insertion 115 in the circuit causes the dynamo voltage and current delivered by its armature to be reduced to such an amount that the attractive force exerted by the controlling magnet upon the armature 22 is insufficient to hold 120 the armature against the force of the spring 18' which results in the resistance 36 being short-circuited by steps and in a pronounced strengthening of the current through the field winding of the dynamo. 125 The voltage will then rapidly rise again causing increase of the charging current through the series coil 9 which in turn results in the attraction of the armature 22 and the insertion by steps of the resistance 130

36 in the field circuit. This again causes the dynamo voltage to be rapidly reduced as before and this sequence of action continues, the series winding 9 responding to 5 the total current delivered by the dynamo to the battery and to any of the translating devices which may be in use. This action results in the armature 22 being given a vibratory movement and causing a fluctuating 10 current to flow from the dynamo armature which fluctuating current integrates to a substantially steady current.

When the vibratory contacts 25, 26 short-circuit the high resistance as above explained, the voltage of the dynamo rapidly builds up, but although this rise in voltage is extremely rapid, there is a smooth, gradual rise in voltage and not such an abrupt or instantaneous one as occurs by 15 cutting out a resistance in series with a device across a constant voltage circuit and in the absence of inductive effect. This rapid smooth rise in voltage at the dynamo brushes causes a rapid but smooth increase in the 20 current through the work circuit and through the series coil 9. This current will continue to increase until the magnetic pull upon the armature 22 separates the contacts 25, 26, successively from the fixed contacts 25 by the sliding and hammer blow quick action above described. The resulting introduction 25 of the resistance in the field circuit instantly prevents the dynamo voltage from increasing any further and it begins to 30 rapidly fall, as well as the current in the work circuit passing through the series coil 9, although this rapid fall of current is a gradual, smooth reduction of current. If not arrested, the voltage of the dynamo 35 would be so reduced as to cause current from the battery to flow backward in the circuit to the dynamo armature. This would cause the current in the series coil 9 to oppose the effect of the shunt coil 8 and thereby cause 40 the instantaneous opening of the main circuit by the armature 12. But before such a condition is reached, the current through the series coil 9 in its fall from its maximum value reaches such a reduced value that the 45 spring 18' overpowers the magnetic force exerted upon the armature 22 and short-circuits the resistance 36 as above described. This checks the fall of voltage of the dynamo and the fall of current in the work 50 circuit and again causes the voltage of the dynamo and current delivered thereby to rapidly and smoothly build up until the magnetic force again forcibly and quickly separates the contacts 25, 26 from the fixed 55 contacts by a hammer blow action, as above stated; this action being constantly repeated.

The short-circuiting or cutting out of the resistance 36 causes the current in the series coil 9 to rise rapidly until the resistance controlling contacts are separated. This is due

to the proportion of the field winding and resistance 36 and also due to the fact that the ohmic resistance in the circuit including the dynamo armature and the battery is extremely low, a comparatively small increase 70 in the voltage of the dynamo making a large change in current through the battery and series coil 9. But even a large change in the current through the battery does not materially affect the voltage across the battery terminals and therefore upon the lamps or other translating devices, because the internal resistance of the battery is so low that the increase of voltage due to the current passing through the low battery resistance 80 is very low compared with the normal counter volts of the battery and the counter volts in the battery are substantially independent of the current through the battery. It is practically impossible for the resistance controlling contacts to stick or "freeze" as it is sometimes called. If they should remain closed, the magnetic force tending to pull the contacts open, will rise many times the normal force needed to overcome the spring 85 18' and the current through the series winding 8 would continue to rise until the contacts were forcibly separated. Moreover, the sliding action of the contacts and the hammer blow action of the armature very 90 greatly assists the controller in properly performing its function continuously even under very severe conditions of operation.

It will be understood that the armature 12 serves as an automatic protective switch, insuring that the dynamo will be connected in circuit with the battery only when the dynamo voltage is sufficiently high and that if from any cause the dynamo voltage becomes abnormally reduced or a reversed current 100 should flow from the battery to the dynamo through the series winding 9, the magnetization of the controlling magnet is reduced to such an extent that the spring 18 overcomes the magnetic attraction of the 105 armature and breaks the charging circuit with a quick hammer blow action in the manner above described. The charging circuit can not again be closed until the voltage of the armature has risen sufficiently high.

While the controller is above described as having a series and shunt winding and is adapted to make the armature circuit and control the field circuit of a shunt machine, it will be understood that this invention is 110 applicable to regulators and dynamos of other types, and to the regulation and control of electricity in various ways and to various forms of controlling systems.

Having thus described my invention, what 115 I declare as new and desire to secure by Letters Patent of the United States is:—

1. In an electric regulator, an electromagnet, a pivoted member moved by said magnet, a plurality of contacts yieldably sup- 120

ported on said member, a plurality of corresponding fixed contacts, and means for causing said yieldably mounted contacts first to move slidably across the fixed contacts and 5 then by a hammer blow by said member out of engagement with said stationary contacts in succession.

2. In an electric regulator, an electromagnet, a pivoted member moved by said magnet, a plurality of contacts yieldably supported on said member, a plurality of corresponding fixed contacts, and means for causing said yieldably mounted contacts to move out of engagement with said stationary 10 contacts in succession and for separating the contacts by a hammer blow.

3. In an electric regulator, an electromagnet, a fixed contact, a pivoted armature, a movable contact and a member carrying the 20 same mounted on said armature, the mounting of said member on said armature comprising means to constrain the movement relative of the contact carried thereby to a direction oblique to the direction of movement 25 of the armature, and means for the armature to separate the movable contact from the fixed contact by a hammer blow.

4. In an electric regulator, an electromagnet, a fixed contact, a pivoted armature, a 30 movable contact and a member carrying the same mounted on said armature, the mounting of said member on said armature comprising means to constrain the relative movement of the contact carried thereby to a direction oblique to the direction of movement 35 of the armature.

of the armature, and means for the armature to actuate the movable contact by a hammer blow.

5. In an electric regulator, an electromagnet, a fixed contact, a pivoted armature, a 40 movable contact and a member carrying the same mounted on said armature, the mounting of said member on said armature comprising means to constrain the relative movement of the contact carried thereby to a direction oblique to the direction of movement 45 of the armature, and means for the armature to engage the movable contact with the fixed contact by a hammer blow.

6. In an electric regulator, an electromagnet, a fixed contact, a pivoted armature, a movable contact and a member carrying the same mounted on said armature, the mounting of said member on said armature comprising means to constrain the relative movement of the contact carried thereby to a direction oblique to the direction of movement 55 of the armature, and means for the armature to separate the movable contact from the fixed contact by a hammer blow and to engage the movable contact with the fixed contact by a hammer blow.

In testimony whereof I affix my signature, in presence of two witnesses.

CAROLYN G. LEONARD,
Administratrix of the estate of Harry Ward Leonard, deceased.
